UNITED STATES PATENT OFFICE.

CLARENCE HARMAN, OF OMAHA, NEBRASKA.

SEWING-MACHINE.

SPECIFICATION forming part of Letters Patent No. 443,395, dated December 23, 1890.

Application filed February 18, 1890. Serial No. 340,840. (No model.)

To all whom it may concern:

Be it known that I, CLARENCE HARMAN, of Omaha, in the county of Douglas and State of Nebraska, have invented a new and Improved Sewing-Machine, of which the following is a full, clear, and exact description.

My invention relates to improvements in sewing-machines; and the object of my invention is to make a simple, strong, durable, and inexpensive machine which will be fully as efficient in operation as the machines of a more complicated construction.

To this end my invention consists in certain features of construction and combinations of parts, which will be hereinafter fully described, and specifically pointed out in the claims.

Reference is to be had to the accompanying drawings, forming a part of this specification, in which similar letters of reference indicate corresponding parts in all the figures.

Figure 1 is a vertical section of the entire machine. Fig. 2 is an inverted plan of the same. Fig. 3 is a vertical section on the line $x x$, looking in the direction of the arrows. Fig. 4 is a broken detailed view of the feed-shaft and crank. Fig. 5 is a detailed view of the feed-bar and feed-dog. Fig. 6 is a detailed view of the presser-foot. Fig. 7 is a vertical section, with the hand-wheel removed, on the line $z z$, looking in the direction of the arrows. Fig. 8 is a front elevation of the feed-regulator attachment. Fig. 9 is a detailed view of one of the forks of the shuttle-lever, with the block and crank connection therewith. Fig. 10 is a vertical section on the line $y y$, looking in the direction of the arrows. Fig. 11 is a section on the line $w w$, showing the groove in the feed-rocker. Fig. 12 is a vertical section of the connection between the feed-lifter shaft and the shuttle-lever. Fig. 13 is a detailed view of the shuttle-carrier, Fig. 14 is a perspective view showing the connection of the shuttle-carrying lever and means for adjusting the feed with the main shaft.

The bed-plate A, arm B, and the needle and tension operating mechanism of the machine are of the usual construction and will need no detailed description, as they form no part of my invention.

My invention consists, chiefly, in the shut-

tle-carrying mechanism, the stop-motion, the feed mechanism, and the regulator for the same. The main shaft C of the machine is 55 provided with a crank C', which operates the shuttle-lever D. The shuttle-lever D is formed from a single piece having a vertical portion, which terminates in a bifurcated upper end D', a horizontal portion, which extends beneath the bed-plate and to the end of which the shuttle-carrier E is attached, with a thickened portion D² at the point where it is pivoted to the bed-plate, and with a forwardly-extending arm D³, which is pivoted to the inner portion of the arm B. The shuttle-lever is pivoted to the bed-plate A and arm B of the machine by means of suitable pins or screws a , which should be in vertical line with each other, so that the lever D may oscillate freely thereon. By providing the lever D with said forwardly-extending arm I utilize space in the hollow machine-arm B which is not otherwise available, and leave the space in rear of the vertical portion of the lever 75 free for operation of another part, hereinafter referred to.

Between the arms of the fork D' of the shuttle-lever are two blocks F, having recesses F' therein, which fit upon the ball C² 80 of the crank C', and from the recesses F' extend tapering recesses F², through which the crank C' extends. The blocks are arranged upon each side of the crank and have smooth backs, which press against the inner faces of 85 the fork D' of the shuttle-lever and may move thereon, so that as the crank revolves it will move the blocks F and cause the shuttle-lever to oscillate upon the pivots a and impart an oscillating motion to the shuttle-carrying end 90 of the lever. A screw b passes through the lower portion of the fork D', by means of which it may be adjusted upon the blocks F.

Attached to the terminal end of the horizontal portion of the shuttle-lever is a shuttle-carrier E, which is open at the top, so that the shuttle H may be easily inserted therein, is provided with a spring E', which lies flatwise in the carrier and presses against the shuttle, and which is turned up at one end 95 and removably attached to the end of the shuttle-carrier with suitable ends, which approximate to the shape of the shuttle, so as to hold it firmly in place, with a face-wall E³,

against which the shuttle bears, and with a shank E^2 , by which it is connected with the shuttle-lever.

Attached to the shaft C near the crank C' is an eccentric J, which is inclosed by an eccentric-strap J' , having a depending arm or rod J^2 , which extends downwardly inside the arm B, and is attached to one end of the feed-rocker K by a suitable screw. The feed-rocker K is pivoted to the stud d , which is suitably attached to the arm B by a screw e , so that as the shaft C, revolves, causing the eccentric-strap J' and arm or rod J^2 to move vertically, the rocker K will be tilted upon its pivot e .

The feed-rocker K is provided with a longitudinal groove K' , in which moves the roller f , which is pivoted by means of a screw f' to the upper end of the connecting-rod L. The lower end of the rod L is pivoted to the crank M' of the feed-shaft M by the screw g , and the upper portion of the rod is provided with a longitudinal slot L' , in which moves a pin of the feed-regulating mechanism, as herein-after described.

The feed-shaft M is mounted in suitable bearings upon the under side of the bed-plate A, and near the front edge thereof is provided with the laterally-extending crank M' , which connects with the main shaft C by the train of mechanism already described and which oscillates the feed-shaft, and at the other end with a vertical crank M^2 , which is pivoted to one end of the feed-bar N, and by means of which the feed-bar is reciprocated.

The feed-bar N is provided with a feed-dog N' , which projects through a slot in the plate A in the usual manner, and which is suitably attached to the feed-bar, the upper surface of the feed-dog being roughened in the usual manner that it may engage any cloth or other material with which it comes in contact and force it through beneath the needle. One end of the feed-bar N is supported upon the crank M^2 , as shown, and the other end is forked, as shown, and the forked end is supported by a roller h , which is pivoted to the laterally-extending crank P' of the feed-lift shaft P, which is supported in suitable bearings upon the other side of the machine. The feed-lift shaft P is also provided with a depending vertical crank P^2 , which is attached to the same near the opposite end from the crank P' , said crank P^2 terminating in a ball P^3 , which is inclosed by a socket j' of the connecting-rod j , thus making a ball-joint connection. The rod j extends across to the shuttle-lever D, and is pivoted to the under side thereof by a screw l , so that the motion of the shuttle-lever will be communicated to the shaft P, causing said shaft to oscillate, thus raising and lowering the crank P' and the feed-bar N, to the forked end of which it is connected.

The outer end of the main shaft C is bored out, as shown, and a rod m inserted in the recess thus formed. The inner end of the rod m is provided with a pin m' , which projects

through suitable slots n in the shaft C and fits within a recess Q' in the loose pulley Q. The other end of the rod m projects beyond the end of the shaft C, is screw-threaded, as shown, and is provided with a hand-nut R, which fits the thread thereof. The pulley Q is mounted loosely upon the shaft C, and between the pulley and the nut R is the usual hand-wheel S, which is fixed to the shaft by means of a set-screw p . The pulley Q, to which the driving-belt is attached, will therefore turn upon the shaft without running the machine; but by turning the hand-nut R the pulley Q will be forced against the hand-wheel S by means of the rod m and pin m' , and as the hand-wheel is fixed to the shaft the shaft will be turned and the machine operated.

The length of the feed—that is, the distance the dog N' travels at each stroke—is regulated by the position of the roller f in the groove K' of the rocker K as motion is communicated from said rocker by means of the roller f , connecting-rod L, shaft M, feed-bar N, and their connections to said dog. For instance, if the roller f were in the center of the rocker K, there would be no motion transmitted to the rod L, and as the roller is forced toward the ends of the rocker the length of the stroke will be increased. It will be observed also that if the roller is at one side of the center and is changed to the other side the stroke will be reversed and the machine will feed in the opposite direction.

To afford means of changing or reversing the stroke of the feed, a curved bar T is pivoted at its elbow to a bracket T' beneath the plate A, one end of the bar extending upwardly to a point opposite the slot L' of the rod L, with which it connects by a pin t , and the other end extending up through a slot T^2 of the curved plate T' on the upper side of bed-plate A and having a thumb-nut r attached thereto, by means of which it may be fixed in any desired position on the plate. By loosening the thumb-nut r and tilting the bar T the rod L and roller f will be moved and the length of the feed-stroke changed or reversed. The thumb-nut may then be tightened, thus making the stroke permanent. It will thus be seen that the stroke may be instantly changed, and that by means of the regulating mechanism the machine will feed in either direction, as desired.

In order that the machine may feed equally well in either direction, I provide a peculiarly-formed presser-foot u, having a flat bearing-surface and having the front and rear portion u' slanted upwardly, as shown.

The machine operates as follows: When the pulley Q is forced against the hand-wheel S, motion will be communicated to the shaft C, and as the shaft revolves the crank C' thereof will actuate the blocks F and move the bifurcated end of the shuttle-lever D, causing said lever to oscillate upon the pins a and imparting a reciprocating or slightly-oscillating motion to the shuttle-carrier E and shut-

tle H, which works in relation to the needle in the usual manner. As the shaft C revolves, it will also oscillate the eccentric-strap J' by means of the eccentric J, thus imparting a vertically-reciprocating motion to the rod J² and oscillating the feed-rocker K, to which it is attached. The feed-rocker will in turn move the rod L by means of the roller f and pin f'. The rod L will move the crank M' and oscillate the feed-shaft M, which by means of the vertical crank M² will give the necessary reciprocating motion to the feed-bar N and dog N'. As the horizontal portion of the shuttle-lever D is connected to the rod j, it will reciprocate said rod, which will tilt the crank P² and oscillate the shaft P. The shaft P will in turn oscillate the crank P', thus giving a vertical movement to the feed-bar N and dog N' by means of the roller h, which fits in the bifurcated end of the feed-bar. It is necessary that the feed-bar should have this movement, otherwise the dog N' would move the cloth back and forth without feeding it in either direction. By attaching the parts as described they will be so timed that the feed-bar will be given a stroke at each revolution of the main shaft and stroke of the needle.

In ordinary machines the shuttle is moved back and forth in a raceway, thus causing a great amount of friction and wear, which will be entirely obviated by the use of my shuttle-carrier.

Having thus described my invention, I claim as new and desire to secure by Letters Patent—

1. In a sewing-machine, the right-angled shuttle-carrying lever D, having the forked

vertical extension D', and the forwardly-extended arm D³, in combination with the crank-shaft C, the needle-bar, the hollow arm B, and bed-plate A of the machine, said lever being pivoted to the arm and bed-plate at points between itself and the needle-bar, as shown and described. 40

2. The combination, with the shaft C, having a transverse slot and a longitudinal bore that traverses the latter, of the hand-wheel S and pulley Q, mounted side by side and respectively fixed and adapted to slide on the shaft, the rod m, fitted in the aforesaid bore and having a cross-pin m', which works in contact with a smooth surface on the inner end of the pulley, and the hand-nut R, applied to the outer threaded end of the rod, as shown and described, whereby upon turning the hand-nut the pin m' forces the contiguous flat surfaces of the pulley and hand-wheel into contact, as specified. 45

3. In a sewing-machine, the grooved oscillating rocker K, pivoted to the head of the machine, in combination with the rod J², pivoted to one end of said rocker, the slotted connecting-rod L, having roller f, working in the rocker, the pivoted bar T, for shifting said rod to vary the throw, the cranked main shaft and its eccentric, the vertically-oscillating shuttle-carrying lever, and the shuttle and other directly co-operating stitch-forming mechanism, the shafts M and P, cranks M' 50 M², and reciprocating bar N, all as shown and described. 55
